(57) **CLAIM**

The ornamental design for a ceiling fan as shown and described.

DESCRIPTION

FIG. 1 is a top perspective view of a ceiling fan, showing my new design.

FIG. 2 is a bottom perspective view thereof.

FIG. 3 is a top view thereof.

FIG. 4 is a bottom view thereof.

FIG. 5 is a front view thereof.

FIG. 6 is a rear view thereof.

FIG. 7 is a right-side view thereof; and,

FIG. 8 is a left-side view thereof.

The broken lines depict portions of the ceiling fan that form no part of the claimed design. The ceiling fan includes a symbolic jagged break along the length of the blades drawn in broken lines. The broken break lines and the area between the break lines forms no part of the claimed design.
